Matthew W. Mitchell

(57) **CLAIM**

The ornamental design for a backpack having integrated solar panels, as shown and described.

DESCRIPTION

FIG. 1 is a front perspective view showing my new design;
FIG. 2 is a back perspective view of the invention;
FIG. 3 is a front view of the invention;
FIG. 4 is a back view of the invention;
FIG. 5 is a side view of the invention, as seen from the right side of FIG. 3;
FIG. 6 is a side view of the invention, as seen from the left side of FIG. 3;
FIG. 7 is a bottom plan view of the invention; and,
FIG. 8 is a top plan view of the invention.
